UNITED STATES PATENT OFFICE.

HENRY E. WALLIS, OF TERRE HAUTE, INDIANA, ASSIGNOR TO WALLIS STOKER AND MANUFACTURING CO., OF TERRE HAUTE, INDIANA, A CORPORATION OF INDIANA.

ARCH-HANGER FOR FURNACES.

No. 874,464.

Specification of Letters Patent.

Patented Dec. 24, 1907.

Application filed April 12, 1907. Serial No. 367,808.

To all whom it may concern:

Be it known that I, HENRY E. WALLIS, a citizen of the United States, residing at Terre Haute, in the county of Vigo and State of Indiana, have invented certain new and useful Improvements in Arch-Hangers for Furnaces, of which the following is a specification.

In the setting of chain-grate stokers, a fire brick ignition arch is suspended over the initial end of the structure where, after it has become heated, it will subject the incoming fresh fuel to its radiated heat. The bricks of which this arch is composed become broken and the hangers warped so that difficulty has been heretofore experienced in replacing them because the hangers for suspending the bricks have been such as to interlock the several series and thus require a removal of the entire arch.

The object of my present invention is to provide an improved hanger for arched bricks, the construction being such that a single series of bricks or a single hanger with its series of bricks may be removed and new bricks or a new hanger with its series of bricks inserted without disturbing the remainder of the arch.

The accompanying drawings illustrate my invention.

Figure 1 is a vertical section of a chain-grate and setting provided with my improved arch hanger; Fig. 2, a side elevation of said hanger in partial vertical section; Fig. 3, a transverse section of a pair of said hangers and associated bricks, the detachable hook being omitted, and Fig. 4, a perspective view of the detachable hook.

In the drawings, 10 indicates channel-like hanger comprising a pair of parallel depending fingers or flanges 11—11 each, provided at its lower edge with an inturned lug or flange 12 adapted to be received in the side grooves 13 of the arch bricks 14. Each hanger 10 is provided at one end with a hook 15 and at the opposite end is provided

with an opening 16 through which may be projected a hook 17. Hook 17 is provided at its inner end with a base 18 adapted to fit within a socket 19 formed in hanger 10 at 50 the inner end of opening 16.

The setting is provided with a pair of transverse beams 20 and 21 arranged above the stoker structure in the usual well known manner. As many hangers 10 as may be 55 necessary are then supported upon the beams 20 and 21, the hooks 15 resting upon the foot of beam 20 while hooks 17 rest upon the foot of beam 21. The bricks 14 are slipped into the hangers 10, as clearly shown 60 in Fig. 3, and each series of bricks abuts the adjacent series so as to fully protect the hangers from the heat of the fire. When the bricks become broken the hangers will become warped by the heat and in order to replace any hanger it is merely necessary to 65 swing hook 17 of the injured hanger so as to withdraw it from the beam 21, whereupon the hanger may be dropped down away from the others without disturbing the 70 remainder of the arch.

I claim as my invention:

1. An arch-hanger, comprising a main body having a pair of depending fingers each provided with an inwardly projecting lug, 75 and a pair of hanger hooks carried by the main body, one of said hooks being movable.

2. An arch-hanger, comprising a main body having a pair of depending fingers each provided with an inwardly projecting lug, 80 an inwardly projecting hook carried by said body at one end, and a movable hook projected through the main body at the other end.

In witness whereof, I, have hereunto set 85 my hand and seal at Terre Haute, Indiana, this the 8th day of April, A. D. one thousand nine hundred and seven.

HENRY E. WALLIS. [L. S.]
